UNITED STATES PATENT OFFICE.

EDWARD O. SCRIVEN, OF NEW YORK, N. Y., ASSIGNOR TO WESTERN ELECTRIC COMPANY, INCORPORATED, OF NEW YORK, N. Y., A CORPORATION OF NEW YORK.

METHOD AND SYSTEM OF HIGH-FREQUENCY TRANSMISSION.

Application filed September 29, 1919. Serial No. 327,039.

This invention relates to methods and systems of high frequency transmission and more particularly to multiplex carrier wave signaling in which high frequency reinforcing oscillations of the carrier frequency are combined at a receiving station with the received carrier oscillations.

An object of the invention is to make possible two-way transmission with the same carrier frequency and at the same time to secure an exact correspondence in frequency between the carrier frequency of the oscillations received at each station and the reinforcing oscillations at that station.

15 A feature of the invention is the derivation of all of the carrier and reinforcing oscillations used in a multiplex system at both terminals of the high frequency line or both radio stations, as the case may be, from control oscillations produced by a single oscillator.

20 A further feature of the invention is the arrangement whereby the reinforcing oscillations are applied to the output circuit 25 of a uni-directionally conducting detector or demodulator in order to prevent transmission of these reinforcing oscillations to the high frequency line.

According to the present invention, the 30 different frequency carrier oscillations or carrier waves are produced by first generating oscillations called "base frequency" or "control" oscillations as, for example, 5000 cycles. These base frequency oscillations 35 are then distorted to produce harmonic frequency oscillations as, for example, of 10,000, 15,000 and 20,000 cycles, and the harmonic frequency oscillations are then separated so that oscillations of one particular 40 harmonic frequency may serve as one carrier wave and oscillations of other harmonic frequencies as other individual carrier waves. It is desirable to be able to carry on two-way communication using waves of 45 the same carrier frequency for transmission in each direction. This may be accomplished by transmitting part of the base frequency oscillations from the station where they are produced to the receiving station 50 with which communication is to be maintained. At the receiving station, the received base frequency oscillations are distorted in the same manner as at the trans-

mitting station to produce carrier waves for the return transmission. 55

According to the method of carrier wave reception termed "homodyne," the amplitude of the signal obtained from the received carrier wave when detected or demodulated is intensified by combining the 60 modified or modulated carrier wave oscillations as received with locally generated reinforcing oscillations of the carrier frequency. This method of reception is disclosed and claimed in United States Patent 65 1,330,471, patented February 10, 1920, to B. W. Kendall. If these locally generated or reinforcing oscillations differ in frequency from the carrier frequency of the received oscillations, beats of the difference 70 frequency are produced and may be manifested as a sound or noise which interferes with a distinct reception of the signal. An important feature of this invention lies in the use of a portion of the carrier wave oscillations produced at a station to reinforce the modified oscillations of the same carrier frequency received at that station. It will, 75 therefore, be clear that all of the carrier oscillations transmitted in both directions in 80 the various two-way transmissions of a multiplex system as well as the reinforcing oscillations supplied to the receiving circuits are derived primarily from a single source, the base-frequency oscillator. The power 85 output of the base-frequency oscillator may, however, be very small, since amplifiers operating substantially without distortion are available to increase the magnitude of a fluctuating current to any desired degree. 90

It is frequently highly desirable that no oscillations of the carrier frequency be transmitted through the ether or over the conducting multiplex circuit, as the case 95 may be, except during transmission of signals or control impulses. It is further desirable that during the transmission of signals or control energy, the envelope of the modified carrier oscillations, as transmitted, be directly proportional to the signal or 100 control impulses or, in other words, that there be no unmodulated component of the transmitted carrier wave. The first of these objects, namely, the prevention of transmission of carrier frequency oscillations, except during intentional transmission, is ac- 105

complished by two different expedients. For the outgoing high frequency channel, a modulator of the general balanced type disclosed in United States Patent 1,343,306, 5 patented June 15, 1920, to J. R. Carson, is used. This modulator is placed between the source of carrier oscillations and the high frequency line of transmitting antenna and permits no carrier waves to pass to 10 the high frequency line except as modified or modulated waves varying substantially in direct proportion to the low frequency waves or impulses impressed on the modulator. For the incoming channel, a uni-directionally conducting detector or demodulator, preferably of the thermionic type, is used and the local source of reinforcing oscillations is connected to its output circuit and is thus prevented by the uni-directionally conducting characteristic of 15 the detector from supplying high frequency oscillations back through it to the high frequency line. It follows, therefore, that waves of carrier frequency are excluded 20 from the high frequency line except during signal or control transmission and that during such transmission, the envelope amplitude of the high frequency carrier wave is directly proportional to the signal or control wave.

This invention is applicable to telephony, telegraphy or any other form of electrical signaling or transmission. Although useful for radio signaling, it is of particular 25 importance in wire line signaling, not only in that it enables a number of telephone or other communications to be carried on simultaneously, but also because this multiplex carrier system may be applied to present day signaling lines, thus increasing the 30 number of messages which they may transmit without interfering with the ordinary lower frequency signal currents which they at present use.

45 In the drawing, Fig. 1 illustrates diagrammatically, the circuits and apparatus at one terminal of an ordinary signal line on which the high frequency system of the present invention has been composed, and 50 Fig. 2 illustrates diagrammatically, the circuits at the opposite terminal of the same composed line but with certain modifications. Referring to Fig. 1, the ordinary signal line to be composed is indicated at 55 1. A low frequency line 2 of the usual type indicated as a telephone line is connected by two-way repeating apparatus 3 including three-element vacuum tube amplifiers of the 60 thermionic type to incoming channel 4 and outgoing channel 5 which are conjugately connected to composed line 1. Both lines 1 and 2 are balanced with respect to their conjugate connections by networks N each of which simulates the characteristic 65 impedance of the line which it serves to bal-

ance for currents of all frequencies transmitted by that line. Since high frequency currents are also to be transmitted over channels 4 and 5, it is necessary to provide means to exclude them from line 2 and its 70 connections which might otherwise dissipate their energy. Such high frequency currents are excluded from the incoming side of the repeater 3 by a low pass filter of the type described in U. S. patent to Campbell, No. 75 1,227,113 patented May 22, 1917. This particular filter consists of a plurality of similar sections each having series inductance and shunt capacity and its electrical characteristics are such that it transmits currents of the range of essential speech frequencies as, for example, 100 cycles up to 2500 cycles with negligible attenuation, while substantially excluding currents of all 80 frequencies outside this range. High frequency currents in outgoing channel 5 are excluded from the outgoing side of repeater 3 by reason of the well known uni-directionally conducting characteristic of the 85 thermionic amplifier connected therein. The telephone station of line 2 may, therefore, carry on two-way communication over composed line 1 without interference from the high frequency carrier currents.

90 Turning now to the high frequency circuits, 6 represents a thermionic oscillator which produces oscillations of base or control frequency, for example, 5000 cycles. Oscillator 6 overloads a thermionic repeater 95 7 connected to it by supplying to the input circuit of the repeater, oscillations of greater amplitude than the repeater is able to repeat without distortion. The repeated oscillations in the output circuit of repeater 7 will accordingly be of non-sinusoidal wave 100 form and are, therefore, the equivalent of a base frequency current of sinusoidal wave form and a series of currents of frequencies which are multiples of the base frequency, that is, harmonic frequencies. The repeater 105 7 will hereinafter be termed a harmonic producer. The output circuit of harmonic producer 7 is provided with a plurality of 110 tuned selecting circuits 8, 9, and 10 each comprising a tuned path bridged across the output circuit and a similarly tuned loop inductively related thereto. Selecting circuits 8 select currents of the base frequency and supply them through an amplifier and a filter 11 to outgoing channel 5 and thence 115 to line 1. Filter 11 is of the Campbell type and freely transmits oscillations of the base frequency, while substantially extinguishing currents of frequency appreciably differing therefrom. It therefore assists in 120 preventing the transmission of harmonic frequency currents from the harmonic producer to channel 5 and it serves to exclude 125 high frequency currents in channel 5 from the harmonic producer circuits.

Selecting circuits 9 select currents of a particular harmonic as, for example, 15,000 cycles and apply them as a carrier wave to circuit 12. In a similar manner, circuit 10 selects current of a different harmonic frequency and transmits it to circuit 13. There may be as many of such selecting circuits each selecting a different carrier wave as is desired, depending merely upon the number of different frequency carrier waves which are to be used.

A signal line 14 of the usual type, illustrated in the drawing as a telephone line, has terminal connections similar to those of line 2 with its repeater 3. However, the circuits 15 and 16 associated with line 14 are not repeater circuits in the sense that they serve merely to transfer speech currents to and from line 14. The function of circuit 15 is to modulate carrier frequency oscillations in accordance with the currents transmitted from the telephone station of line 14 and to transmit such modulated carrier frequency oscillations to outgoing channel 5. The function of circuit 16 is to select from incoming channel 4, the particular modulated carrier waves which "carry" the return communication from the communicating station at the opposite terminal of line 1 and to cause these selected modulated waves to reproduce in line 14, speech current by which they were modulated. Circuit 15 includes a balanced modulator M of the type disclosed in United States Patent No. 1,343,806 and a band filter 18 of the Campbell type, connected in tandem. Speech frequency currents are applied from line 14 to the divided input circuit of modulator M and carrier frequency oscillations are applied by circuit 12 to the potentiometer 17 in the common input path of the modulator. As is well known, a modulator of this type will repeat no carrier current from circuit 12 in its input circuit, except at such times as an electromotive force is applied across its divided input circuit when it will repeat the carrier currents in its output circuits with a magnitude directly proportional to the amplitude of the wave applied to the divided input circuit. The Campbell wave filter 18 transmits currents of a band frequency which may range either up or down or both up and down from the carrier frequency by the essential speech frequency range which has been previously stated. Filter 18 serves to define, as desired, the range of the band transmitted to prevent low frequency currents from being repeated from line 14 through the modulator M to channel 5 and to exclude from the output circuit of the modulator, the foreign frequency currents of channel 5 which might otherwise enter into its modulating action and produce cross-talk at some receiving station.

Circuit 16 includes a band filter 19 similar to 18, a balanced detector or demodulator D, a thermionic amplifier and a low pass filter 20 similar in electrical characteristic to the low pass filter of repeater 3. Filter 19 selects from incoming channel 4, the modulated oscillations of a particular carrier frequency and applies them across the divided input circuit of balanced detector D. The common path of the output circuit of detector D includes a space current source and a choke coil in series. Shunted around the source and choke coil, is an alternating current path comprising a capacity element and a potentiometer. Across the potentiometer, reinforcing oscillations of the carrier frequency are applied by circuit 12, it being understood that the carrier frequency of the modulated wave received by filter 19 is the same as that of the modulated wave transmitted out to channel 5 by filter 18. The effect of the reinforcing oscillations is both to supply the unmodulated carrier component necessary for demodulation of the received modulated wave components, and to augment the resulting low frequency signal current which detector D supplies to the amplifier. Filter 20 prevents transmission of high frequency currents to line 14.

There may, of course, be any number of lines similar to line 14 and each may be connected to line 1 by circuits similar to those of line 14 but differing principally in that they are each designed to operate with an individual carrier frequency wave. It will also be clear that line 1 serves to transmit ordinary speech currents from line 2, base frequency oscillations from the harmonic producer 7 and modulated carrier waves for each of the lines 14.

Referring to Fig. 2, the opposite terminal of composited line 1 is illustrated as connected across a single distributing channel 21 instead of to incoming and outgoing channels, such as 4 and 5 of Fig. 1. However, either arrangement may be used at both terminals of line 1.

Connected to channel 21 through a filter similar in characteristics to filter 20, is a telephone signaling line 22 adapted to communicate over the line 1 with line 2. The filter selects incoming speech frequency currents from channel 21 and transmits outgoing speech frequency currents to this channel.

A filter 23, similar to filter 11, selects from channel 21, base frequency oscillations and transmits them to an amplifier 24 by which a harmonic reproducer 25, similar in function and operation to harmonic producer 7, is overloaded. The selecting circuits 26 which separate the various harmonic frequency carrier waves are series tuned loop circuits and each corresponds in the frequency to which it is tuned to a selecting

circuit, such as 9 or 10, at the other terminal of line 1, shown in Fig. 1.

Connected across channel 21 are band filters 27 corresponding in number to the lines 28 which communicate with lines 14. Each filter 27 must transmit a range of currents including the ranges of both filters 18 and 19 associated with the line 14 with which it maintains communication. A single filter 27 with its associated line 28 is illustrated, it being understood that the others are similar in every respect except as to changes in their design necessary for the different carrier frequencies involved. Filter 27 is connected to a balancing network through a balanced transformer or hybrid coil with which are associated an incoming circuit 29 and an outgoing circuit 30. Incoming circuit 29 includes a demodulator D having a constant current choke coil in its output circuit and a filter 31 of characteristics similar to those of elements D and 20 respectively in circuit 16 of Fig. 1. Reinforcing oscillations of carrier frequency are supplied to the demodulator by the proper selecting circuit 26 of the harmonic reproducer 25. It follows that filter 31 transmits to line 28, the reproduced signaling currents of line 14. The outgoing circuit 30 includes filters and a balanced modulator M of the type described in connection with circuit 15 of Fig. 1. This modulator receives its carrier oscillations from the selecting circuit 26 which supplies reinforcing oscillations to the modulator or detector D of incoming circuit 29. These carrier oscillations are accordingly modulated in accordance with the speech currents of line 28 and are transmitted to line 1.

It will be noted that all of the carrier and reinforcing oscillations at this terminal of line 1 are derived as harmonics of oscillations of base frequency transmitted over line 1 from the base-frequency oscillator and its harmonic producer.

The same principles are applicable to radio signaling and to radio teledynamic transmission generally in so far as the carrier frequency communications are concerned, and if the base frequency and carrier frequencies are sufficiently high to be effectively radiated, transmitting and receiving antennæ may be substituted in lieu of the line 1.

The term carrier wave, as used herein, includes, not only high frequency oscillations of varying amplitude such as are commonly used in radio telephony, but also high frequency waves or currents either merely interrupted or changed in frequency to denote signal or control impulses. This term is, however, not to be confused with high frequency or radio frequency, since it is possible where ordinary telephony is not being transmitted, to transmit over a conducting

line, a large number of different frequency alternating currents ranging from a few cycles per second up to several thousand, each of these different frequency currents serving as an individual carrier.

Although the features of this invention have been described as employed in particular circuits, it is to be understood that the invention is not to be limited thereto, but only by the scope of the appended claims.

What is claimed is:

1. The method of signalling between separated stations which comprises producing at all of the stations a wave of the same frequency and of substantially constant amplitude, deriving at each station from the wave produced thereat a wave for the transmission of signals, producing amplitude variations in the wave so derived to represent the signals to be transmitted, deriving at each station from the wave produced thereat a wave of constant amplitude, and combining the last mentioned wave at a station with the signal modified wave of the same frequency incoming from another station to reproduce amplified signals.

2. The method of two-way carrier wave transmission between stations associated with a common carrier transmission circuit which comprises reinforcing the waves received at each station by oscillations of the carrier frequency of said waves and deriving all of said carrier waves and said reinforcing oscillations from oscillations produced by a single source.

3. A two-way carrier wave transmission system comprising separated stations, means at all of the stations for producing a wave of the same frequency and of substantially constant amplitude, means at each station for deriving from the wave produced thereat a wave for the transmission of signals, means for producing amplitude variations in the wave so derived to represent the signals to be transmitted, means for deriving at each station from the wave produced thereat a wave of constant amplitude, and means for combining the last mentioned wave at a station with the signal modified wave of the same frequency incoming from another station to reproduce amplified signals.

4. The method of two-way carrier signalling comprising modulating in each of a plurality of stations a carrier wave by signals and suppressing transmission of the unmodulated carrier component, transmitting from and receiving at each station the modulation components of the signal-modulated carrier wave, separating the received wave from the wave being transmitted, detecting the received wave by combining it with an unmodulated carrier wave of similar characteristics to the wave used at a distant station for modulation, and deriving at a given station the unmodulated wave for both the

- modulating and demodulating processes from the same carrier wave source.
5. The method according to claim 2 which comprises deriving a plurality of different frequency carrier waves from the oscillations produced by the single source and transmitting each of said carrier waves modified in accordance with an individual signal over a common transmission circuit.
- 10 6. A receiving station comprising means for receiving high frequency oscillations, a balanced unidirectionally transmitting demodulator having a symmetrical input circuit and a symmetrical output circuit, means for impressing received high frequency oscillations upon said input circuit, means for impressing reinforcing oscillations of the carrier frequency of said received oscillations symmetrically upon said output circuit whereby said reinforcing oscillations are prevented from being transmitted to said input circuit or from said output circuit.
- 15 7. A multiplex transmission circuit having a plurality of receiving channels each including an asymmetrically conducting demodulator, and means for supplying locally produced reinforcing oscillations to the output circuit of said demodulator, whereby said reinforcing oscillations are prevented from being transmitted to said transmission circuit.
- 20 8. A system of two-way carrier transmission comprising a plurality of stations, means at each of said stations for receiving carrier oscillations, means for reinforcing said received oscillations by local oscillations of the carrier frequency, and means for deriving all of said carrier oscillations and said reinforcing oscillations from a single oscillation source.
- 25 9. A system according to claim 8 comprising means for compositing a plurality of two-way carrier transmissions on a common transmission circuit.
- 30 45 10. In a two-way carrier telephone system a plurality of stations each having a transmitting and a receiving circuit and a source of oscillations, said sources of oscillations having the same frequency, means in the transmitting circuit of each station for modulating oscillations from the source at said station in accordance with speech, and means in the receiving circuit of each station for combining speech-modulated carrier waves from another station with oscillations from the source at the station at which said receiving circuit is located for producing interaction currents of speech frequency.
- 35 11. A transmission line, a receiving channel and a transmitting channel each connected thereto, a common source of oscillations of a single frequency for supplying carrier oscillations to said transmitting channel and reinforcing oscillations to said receiving channel, and means for preventing interaction of either of said channels upon said source or upon each other.
- 40 12. A receiving system comprising means for receiving high frequency oscillations, a demodulator consisting of two three-element electric discharge devices having separate input and output circuits and having their input circuits oppositely connected to said means, a transmission circuit, said discharge devices having output circuits oppositely connected to said transmission circuit, and means for impressing high frequency reinforcing oscillations on said output circuits.
- 45 13. In a carrier telephone system having stations, sources of carrier oscillations of the same frequency at respective stations, means at each station for modulating oscillations from the respective source by voice control for transmission, means at each station for combining oscillations from the source at the respective station with the incoming voice modulated signal oscillation from the other station, and means responsive to the combined oscillations for receiving the detected voice message.
- 50 In witness whereof, I hereunto subscribe my name this 27th day of September A. D., 1919.

EDWARD O. SCRIVEN.
